[57] **ABSTRACT**

The holder comprises an adjustable frame arranged to rest on the upper rim of an open top waste basket and support a roll of punched computer tape for unreeling by rotation about a horizontal axis upon feeding of the tape endwise through a punched tape reader.

HOLDER FOR FEEDING PUNCHED TAPE

BACKGROUND

1. Field of Invention

The invention is directed to the field of detachable supports for open top receptacles.

2. Description of the Prior Art

Punched tapes are fed into the readers, passed therethrough, and returned to the outside by a feed mechanism built into the reader. Quite frequently, during the production of a final tape, short lengths of tape are punched and then fed through the reader for checking and returned thereby to the outside for such editing or corrections as may be necessary. Heretofore, the practice has been for the operator to hold a roll of punched tape in his fingers so that it can rotate and unreel as a result of the feed mechanism of the reader pulling endwise on the tape, and to allow the returned tape to drop into a waste basket. Having checked the particular length of tape, the operator then takes the tape out of the basket and rolls it up by winding it about his finger.

SUMMARY OF THE INVENTION

The present invention is directed to a frame which can be detachably secured to the rim of an open top receptacle so that the frame will be constrained from lateral displacement. The frame carries a horizontal pintle on which the roll of punched tape is supported for unreeling. The frame and pintle are so arranged that the tape returning from the computer can be discharged into the receptacle on which the frame is supported. The frame is such that it does not interfere with access to the interior of the receptacle so that the tape can be readily removed therefrom. The frame is adjustable for fitting rims of open tops which are circular or polygonal in shape.

Various objects and advantages of the invention will become apparent from the following description wherein reference is made to the drawings.

DESCRIPTION OF THE DRAWINGS

FIG. 1 is a perspective view illustrating a frame embodying the principles of the present invention, showing the frame installed on the rim of the open top receptacle;

FIG. 2 is a fragmentary top plan view of the frame illustrated in FIG. 1;

FIG. 3 is a fragmentary vertical longitudinal sectional view taken on the line 3-3 in FIG. 2; and

FIG. 4 is a fragmentary cross sectional view taken on the line 4-4 of FIG. 2.

Referring to the drawings, a supporting frame 1 is shown in connection with a reader indicated at C and an open top waste basket 2 having about its open top a rim 3. In the form illustrated, the basket is rectangular or square at the top. However, the frame of the present invention is equally applicable to waste baskets or receptacles of which the open top is curvilinear or polygonal.

The rim 3 comprises a radially outwardly extending horizontal flange 3a and depending outer peripheral flange 3b. The frame 1 comprises a body portion 4 carrying at least three arms 5, 6, and 7, which preferably radiate from a common center. The arms 5 and 6 may

be rigid and integral with the body portion 4. The arm 7, however, is separately formed and is telescopically received in the body portion 4 for adjustment endwise to extended and retracted positions. For this purpose, the arm 7 has an elongated slot 8 through which a bolt 9, carried in the body portion 4, is received. A nut 10 is provided for clamping the arm 7 fixedly in selected adjusted positions endwise of the arm 7.

The outer end portions of the three arms 5, 6, and 7 provide supporting means which rest upon the rim 3 of the waste basket. Means are provided to constrain the frame to a fixed position laterally of the open top of the waste basket. In the form illustrated, a simple connecting means is provided by forming on the underside of the arms, respectively, notches such as indicated at 11, which are adapted to receive the upper rim of the receptacle.

The arm 6 provides a pintle for supporting a roll 12 of punched tape, to be fed into the reader, so that the roll can rotate about a horizontal axis. For this purpose, the upper exposed portion of the arm 6 is made semi-cylindrical, as indicated at 13, so as to permit free rotation of the roll 12 supported thereon.

With the notches 11 engaged with the rim 3 of the waste basket, the frame 1 is constrained from lateral displacement whether the open top of the basket is rectangular, circular or other shape. However, it is desirable that the frame be such as it can be lifted readily upwardly off the rim for installing another roll on the arm 6. At the same time, it is desirable that the frame be relatively steady. To this end, resiliently expandable and contractable cushions 14 are provided in the arms 5, 6, and 7, respectively, and are such that in their normal unstressed condition, they extend from the outer ends of the arms inwardly toward the body portion 4 partway across the notches so that they are compressed on installation of the frame on the rim and thus assist in steadyng the frame in position.

Preferably all of the frame, including the body portion 4 and arms 5, 6, and 7 are of an inverted U-shaped cross section, as illustrated in FIG. 4 in connection with the arm 6, and all except the arm 7 are integral and of a relatively stiff plastic material molded in one piece.

In order to install the frame, the bolt 9 and nut 10 are loosened, the notches of the respective arms are engaged with the rim of the receptacle, the frame is adjusted accordingly by adjustment of the arm 7, and the bolt 9 and nut 10 are then tightened.

With this arrangement the frame is prevented from lateral displacement but can be tilted readily for removing the roll 12 from the arm 6 and installing a new roll.

Having thus described my invention, I claim:

1. A punched tape holder comprising a body, said body including at least three supporting arms connected together and spaced apart from each other circumferentially of a predetermined axis and arranged to rest on a horizontal rim of an open top receptacle;

at least one of the arms having means for adjustably extending and contracting said one arm transversely of, and relative to, said axis for adjustment of the body transversely of said axis to different positions parallel to the plane of said rim whereby said one of the arms can be adjusted to be positioned on open top receptacles having openings of dif-

ferent sizes, while the other two arms also rest on said open top; connecting means on at least one of the arms for cooperation with the rim of said receptacle for restraining the body from lateral displacement relative to said open top; and one of said arms including a rigid pintle shaped for receiving thereon an annular roll of punched tape by insertion of the pintle endwise through the central passage of the roll, and having a roll supporting portion between its ends shaped to lie in said central passage and support the roll for rotation during unreeling of the roll by pulling endwise on the tape.

2. The structure according to claim 1 wherein said pintle is a portion of one of the arms which arm has an outer free end receivable through said passage.

3. The structure according to claim 2 wherein the pintle portion of said one of the arms is rounded in cross section at least on the upper surface on which a supported roll would rest.

4. The structure according to claim 1 wherein the

said three arms radiate from a common center.

5. The structure according to claim 4 wherein the connecting means are on at least two of the arms, respectively, and each connecting means is near the outer end of its associated arm.

6. The structure according to claim 1 wherein two of said arms are integral with each other, and said one arm which is extensible and contractable includes said extending and contracting means, whereby said last-mentioned arm is adjustably positionable in different positions.

7. The structure according to claim 1 wherein the connecting means are located on at least two of the arms and comprise notches in the arms and are open downwardly when the body is in operating position.

8. The structure according to claim 7 wherein resilient cushioning means are carried by the arms and are resiliently compressible and expandable in a direction transversely of said axis, and, in their normal unstressed condition, extend in said direction partway across the notches, respectively.
